[57] ABSTRACT

Fire escape apparatus comprising a tightly sealed shaft attached to a building wherein self-closing escape channels are provided to connect each floor of the building downwardly with the shaft, and a main exit is located at the bottom of the shaft with forced draft fan or natural up-draft opening being provided to maintain a higher pressure head in the shaft than that of the building to prevent fire from traveling through the escape channel and thus ensure safety of the escaper.

FIG. 6

FIRE ESCAPE APPARATUS

BACKGROUND OF INVENTION

The conventional fire escape in a building is usually an escape stairway or ladder provided at an emergency exit on each floor. Because of the exit opening, flames usually can get to the escapers. Another kind of fire escape is located in the center of a building with chimney like construction. Such a construction has been found to accelerate fires by providing an easy path therefor. In none of the prior art fire escapes, is escape safe.

SUMMARY OF INVENTION

This invention is a novel fire escape apparatus comprising a tightly sealed vertical shaft attached to a building with stairs and platforms provided therein. At least one self closing escape channel having ladders or chutes, is provided to connect each floor of the building downwardly with the shaft. To prevent fire from getting into the channel or shaft, a higher pressure is maintained in the escape shaft and channel, thus ensuring safety of the escapers.

BRIEF DESCRIPTION OF DRAWING

FIG. 1 depicts a top view of an illustrative embodiment of this invention;

FIG. 2 depicts a partial front view of the embodiment of FIG. 1;

FIG. 3 depicts a partial cut-a-way side view of the embodiment of FIG. 1;

FIG. 4, depicts another illustrative embodiment of this invention showing a forced draft channel; and

FIG. 5 depicts a partial front view of the embodiment of FIG. 4.

FIG. 6 depicts a pictorial view of an illustrative embodiment showing an inclined chute and fan means.

DETAILED DESCRIPTION OF PREFERRED EMBODIMENTS

Turning to FIGS. 1 through 3, there are depicted a tightly sealed shaft 1' attached to building 1. Stairways 2 and platforms 2' and 2'' are located within the shaft 1'. Main exit 3 is located at the bottom of shaft 1'. Channel 6' connects each floor of the building 1 to a lower floor via opening 6, which is normally horizontally disposed, and to corresponding platform 2' via vertical opening 8. Doors 5 and 7 are provided at openings 6 and 8, as shown. The doors may be opened outwardly, or swing biased, to keep them in a normally closed condition, thereby ensuring air tightness. Channel 6' may be vertical and straight, or inclined, to pass through a one floor depth, or to pass through more than a one floor depth. When channel 6' is vertical and straight it is equipped with ladders 9, as depicted. When channel 6' is inclined, a sliding chute may be provided therein. Emergency exit opening 6 is usually located at the end of corridor 10 in building 1.

Turning now to FIGS. 4 and 5, the same embodiment elements are shown bearing the same numeral designations, except in addition, there is attached to shaft 1', an auxiliary channel 11, which is also vertically disposed. Openings 13, with inwardly swinging biased doors, provide therein, are provided between shaft 1' and auxiliary channel 11, to enable natural draft to enter shaft 1'. Alternatively, a forced draft fan may be provided at the bottom opening 12 of auxiliary channel 11 to build a higher pressure in shaft 1' than in building

1. Thus, there would be no opportunity for fire to build up and travel from the building to the channel 6' and shaft 1' through opening 6. Also, door 5 will check the fire.

5 FIG. 6 depicts pictorially the embodiment of the invention. Also, an alternative sliding chute 9' is shown for use in escaping from one floor to the next lower floor. Also, fan 100 is shown for providing forced draft.

To escape a fire in building 1, people will proceed to the end of corridor 10, enter into channel 6' through door 6, climb or glide down channel 6' (depending upon whether there is a ladder or slide) to reach opening 8, and proceed through door 7 to platform 2' on the lower floor. Thereafter, they may easily walk down stairs 2 to platform 2'', and through main exit 3 to the outside. The escape is made safely and rapidly.

15 Fire fighting personnel may utilize the channel 6' as a hiding place. By lifting the door 5, he can easily apply the fire extinguisher or water hose nozzle aimed toward the corridor. Because of the positive pressure maintained in the channel 6', fire in the corridor or building would have the least possibility of licking back to the channel.

20 The walls of escape channel 6' and of shaft 1' and the walls of building 1 adjacent thereto should be of fire-proof material. Lighting facilities may be installed in shaft 1' and channel 6'.

25 The foregoing description is intended to illustrate the invention and not to limit it. Any alternative, variation, or modification thereof, made without departing from the spirit of the invention, should be considered to be within the scope thereof.

30 What is claimed is:

35 1. Apparatus enabling safe escape from a building having a plurality of floors, comprising

a substantially sealed vertically disposed shaft attached to said building, said shaft having disposed therein a plurality of stairs and a plurality of platforms, some of said platforms located substantially about the height of said floors, and an exit located at the bottom of said shaft;

40 at least one channel adjacent said shaft, said channel having at least one horizontally disposed door located on each floor, and means for traveling downwardly from one floor to a lower floor; and vertically disposed doors located at selected floors for egressing from said channel to said platform corresponding to said lower floor.

45 2. Apparatus of claim 1, wherein said channel is of a vertical straight type with a ladder therein and extending at least one floor depth.

50 3. Apparatus of claim 1, wherein said horizontally disposed door, said vertically door, and said exit in said shaft are normally closed to ensure air tightness.

55 4. Apparatus of claim 1, further comprising an auxiliary vertically disposed channel attached to said shaft, said auxiliary channel having openings between it and said shaft with one way swing check doors provided to allow draft into said shaft.

60 5. Apparatus of claim 4, wherein an opening is provided at the bottom of said auxiliary shaft to provide natural draft or forced draft into said auxiliary channel and through said openings between it and said shaft, into said shaft.

65 6. Apparatus of claim 5, wherein a fan is provided at the bottom of said auxiliary channel to provide forced draft.

7. Apparatus of claim 1, wherein said channel is of an inclined type with a sliding chute and extending at least one floor depth.
